(57) **CLAIM**

The ornamental design for a television receiver as shown and described.

DESCRIPTION

1. Television receiver

1.1: Front perspective

1.2: Rear perspective

1.3: Front

1.4: Back

1.5: Left

1.6: Top

1.7: Bottom

1.11: Reference

The claimed design is a television receiver in which the display unit and the case are integrated into one body; the right side view is omitted because it is a mirror image of the left side view; reproduction 1.11 is a reference view showing the state of use with stand; the broken lines indicate portions of the article that form no part of the claimed design; the broken lines shown in reproduction 1.11 illustrate environmental structure and form no part of the claimed design.

1 Claim, 8 Drawing Sheets
